UNITED STATES PATENT OFFICE.

PETER HOBLER, OF CHICAGO, ILLINOIS.

DESIGN FOR A FRAME FOR PORTABLE GRINDING-MILLS.

SPECIFICATION forming part of Design No. 17,051, dated January 4, 1887.

Application filed June 8, 1886. Serial No. 294,554. Term of patent 14 years.

To all whom it may concern:

Be it known that I, PETER HOBLER, of Chicago, county of Cook, and State of Illinois, have invented and produced a new and useful

5 Design for a Mill-Frame, of which the following is a specification, reference being had to the accompanying drawing, forming a part thereof.

The figure represents a perspective of my 10 design, which consists of a circular support.

My design consists in a circular support or base, A, vertical web-legs B and B', and a top plate, C'. The lower ends of the web-legs are somewhat widely extended and attached to the

base-plate, and gradually curve inwardly in 15 the direction of each other as they near the upper end to join the top C'. The legs are also are shaped in cross-section.

What I claim as new is—

The design for a mill-frame, consisting of a 20 base, A, standards B and B', and top C', having the shape and configuration shown and described.

PETER HOBLER.
